UNITED STATES PATENT OFFICE

WILLIAM R. HUTTINGER, OF PHILADELPHIA, PENNSYLVANIA

SWITCH CONTACT

Application filed July 19, 1928. Serial No. 293,884.

My invention relates to switches, and it has for one object the provision of a switch which is capable of being operated with a maximum disalignment of the parts.

Another object of my invention is to provide a switch, wherein the movable member is provided with a ball-and-socket connection to the hinge terminal, so that the movable member may be actuated in a number of different directions.

A further object of my invention is to provide a movable switch member with adjustable contact means for co-operation with a stationary contact member of the switch, so that good contact may be assured when the movable switch member is disaligned with respect to the stationary contact member.

A still further object of my invention is to provide a switch comprising a pair of spaced contact members, a plurality of floating switch elements having a ball-and-socket connection with one of the contact members, and adjustable means carried by the floating switch elements for co-action with the other contact member, so that good contact may be assured for a maximum disalignment of the contact members with respect to the floating elements.

A still further object of my invention is to provide simple and efficient means, whereby uniform contact pressures may be maintained on the hinge and front switch terminals.

Other objects and applications of my invention, as well as details of construction and operation, will be apparent more fully hereinafter, when taken in connection with the accompanying drawings, wherein

Fig. 1 is a front elevational view of a switch compartment with the cover removed, showing one embodiment of my invention;

Fig. 2 is a transverse sectional view taken on the line 2—2 of Fig. 1;

Figs. 3 and 4 are detail, front and side elevational views, respectively, of the switch shown in Figs. 1 and 2;

Figs. 5 and 6 are transverse and longitudinal sectional views taken on the lines 5—5 and 6—6, respectively, of Fig. 3; and

Fig. 7 is a side elevational view of the dis-

connect switch shown in Fig. 2, but with the upper and lower switch terminals further disaligned.

Referring to Figs. 1 and 2, a compartment 1 of a power house is provided with an open side 2 affording access to a truck-type oil switch 3 and a disconnect switch 4 positioned therein. The oil switch 3 is shown as mounted on a truck 5 permitting the removal thereof when repairs are necessary. A difficulty heretofore encountered in connection with such switching equipment is the necessity for very accurately machining the switch parts, so that when the oil switch 3 is moved into the compartment 1 the disconnect switch 4 may be closed. Such machining necessarily increases the expense of the equipment. These undesirable results are overcome in my invention by the provision of a flexible connection between a hinge switch terminal 6, which is mounted on the oil switch 3, and a front switch terminal 7 which is insulatingly mounted on a rear wall 8 of the compartment 1. Such construction permits the closing of the switch 4 with a maximum disalignment of the switch terminal members 6 and 7.

Referring more particularly to Figs. 3 and 4, the disconnect switch 4 is shown as comprising a switch blade or member 9 which serves to connect contact members 6 and 7. The switch blade 9 may comprise a pair of spaced, elongated, floating elements 11 and 12, lower end portions 13 and 14 of which are provided with recesses 15 and 16 which together define a socket 17 for a ball element 18. The ball element 18 is mounted on the upper end portion of the hinge switch terminal 6. A bolt 19 extends through the floating elements 11 and 12 immediately adjacent to the ball element 8, and it is provided with adjustable heads 21 and 22 so as to prevent the separation of the lower end portions of the floating switch elements 11 and 12. The ball-and-socket connection thus afforded between the hinge terminal 6 and the switch blade 9 permits the latter to assume a number of angularly displaced positions.

When the switch terminals 6 and 7 are out of alignment, as shown in Figs. 1 and 3, it is also necessary to provide an adjustable con-

nection between the movable switch blade 9 and the upper terminal member 7 in order to assure good contact therebetween. To this end, I provide upper, inner side portions of the floating elements 11 and 12 with inwardly projecting shoulders 23 and 24 which are formed with spherical recesses 25 and 26 constituting seats for spherical portions 27 and 28 of adjustable contacts 29 and 31, respectively. The recesses 25 and 26 together constitute a socket for the spherical portions 27 and 28 which together form a ball element. The contacts 29 and 31 are provided with flat surfaces 32 and 33 which cooperate with the opposite sides of the front switch member 7. Thus, a ball-and-socket connection is formed between the movable switch blade 9 and the front switch terminal 7, permitting the angular adjustment of the former with respect to the latter in the event of disalignment therebetween.

The contacts 29 and 31 are prevented from dropping from the floating switch elements 11 and 12, when the switch is disengaged from the stationary contact member 7, by means of a pair of studs 34 and 35 which are threaded in the spherical portions 27 and 28 of the contacts 29 and 31, respectively, and extended through openings 36 and 37 in the floating switch elements 11 and 12. The studs 34 and 35 are held in the openings 36 and 37 by means of locking pins 38 and 39 which extend through the portions of the studs 34 and 35, respectively, which project beyond the outer side of the floating switch elements 11 and 12. The openings 36 and 37 are axially elongated to permit the angular adjustment of the studs 34 and 35 when the switch member 11 is out of alignment with the contact member 7.

The contact 29 is provided with a pair of flexible conductors 41 and 42 which are secured to the inner side of the floating switch element 11 at longitudinally spaced points. The contact 31 is similarly provided with a pair of flexible conductors 43 and 44, which are secured to the inner side of the opposite floating switch element 12. These flexible connections in no way interfere with the angular adjustment of the contacts 29 and 31.

A still further feature of my invention is the provision of simple and efficient means, whereby uniform contact pressures may be maintained on the ball element 18 of the hinge contact member 6 and on the front contact member 7. This desired result is accomplished by the provision of a single tension bolt 45 which is positioned substantially midway between the ball element 18 of the hinge terminal 6 and the contact surfaces of the front switch terminal 7. One end of the bolt 45 extends through the floating switch element 11 and is provided with a head 46, while the other end extends through the switch element 12 and is provided with an adjust-

able head 47. A spring 48 is positioned between the adjustable head 47 and the outer side of the switch element 12, so that a spring-tension contact may be obtained between the switch blade 11 and the contact members 6 and 7. It is noted that such tension-adjusting means employs a minimum number of parts and, moreover, assures even spring-contact pressures at the switch terminals 6 and 7.

The switch blade 11 may be locked in its closed position shown in Fig. 3, by means of locking mechanism 49 of known design. As illustrated particularly in Fig. 6, the mechanism may comprise a longitudinally-movable bolt 51, an inner end 52 of which fits under an inner shoulder 53 of the upper front switch terminal 7 when the switch 4 is closed. The bolt 51 is normally maintained in the locked position by means of a spring 54. The bolt 51 may be actuated forwardly from under the shoulder 53 by means of a pivoted member 55 having a shoulder 56 which co-acts with a shoulder 57 of the locking bolt 51. This locking mechanism is mounted on end portions 58 and 59 of the floating switch elements 11 and 12 just above the upper side of the front switch terminal 7.

Assuming that when the truck switch 3 is moved into the compartment 1, the lower contact member 6 is offset laterally with respect to the upper contact member 7, as shown in Figs. 1 and 3. The switch 4 may still be closed without the necessity for adjusting the position of the oil switch 3 or for machining any of the parts. This desired result is due to the fact that the ball-and-socket connection at the hinge terminal 6 of the switch 4 permits the angular adjustment of the switch member 9 to the right, as viewed in Fig. 3, while the adjustable mounting of the contacts 29 and 31 assures the proper engagement of the upper end of the switch member 9 with the front contact member 7.

Should the hinge and front contact members 6 and 7 be further disaligned, as shown in Fig. 7, the ball-and-socket connections between the switch member 9 and the contact members 6 and 7 permits the further adjustment of the switch member 9 into a position wherein good contact conditions may be assured with the switch terminals 6 and 7. If the contact pressures on the terminals 6 and 7 are insufficient, it is necessary only to turn the adjustable head 47 of the tension bolt 45.

While I have shown only one form of embodiment of my invention, for the purpose of describing the same and illustrating its principles of construction and operation, it is apparent that various changes and modifications may be made therein, without departing from the spirit of my invention. I desire, therefore, that only such limitations shall be imposed thereon, as are indicated

in the appended claims or as are demanded by the prior art.

I claim:

1. A switch comprising a pair of terminals, a movable contact member in engagement with said terminals, and means whereby a substantially uniform pressure may be exerted by said switch member on said pair of terminals, said means comprising a tension bolt positioned between said terminals.
2. A switch comprising a pair of spaced contact members, a switch member in engagement with said contact members and extending therebetween, and a single tension bolt so positioned as to assure equal contact pressures by said switch member on said terminals.
3. A switch comprising spaced contact members, a movable switch member in engagement with said contact members, spring means, and a bolt operatively associated with said spring means and said switch member for causing variations in the pressure of said switch member on said spaced contact members, said bolt being so positioned intermediate said contact members as to cause the pressures on said contact members to be substantially equal.
4. A switch comprising a pair of spaced contact members, a movable switch member, means affording said movable switch member a ball-and-socket mounting on one of said contact members, contact means carried by said movable switch member for co-operation with another contact member, and a tension device positioned substantially midway between said contact members for causing a predetermined contact force between said switch member and said contact members.
5. In a switch, the combination with a pair of contact members, of a movable switch member, means affording ball-and-socket connections between at least one of said contact members and said switch member, a tension device for assuring a substantially equal contact pressure on said spaced members, and a locking device for said movable switch member in operative relation to one of said contact members.
6. The combination with a switch member comprising a plurality of floating elements, of a contact member, and means providing a ball-and-socket connection between said contact member and said switch member.
7. The combination with a terminal and a plurality of floating switch elements pivoted thereon, of a second terminal, and means whereby said floating elements may be electrically connected to said second terminal for different disaligned positions of said floating switch elements.
8. The combination with a switch terminal, of a plurality of floating switch elements having a ball-and-socket connection therewith, a second terminal and adjustable con-

tact means in engagement with said second terminal and said floating switch elements.

9. The combination with a switch terminal, of a plurality of floating switch elements having a ball-and-socket connection therewith, a second terminal, adjustable contact means in engagement with said second terminal and said floating switch elements, and a tension bolt positioned to cause substantially uniform contact pressures at said switch terminals.

10. The combination with a pair of switch terminals, a pair of floating switch elements, means for providing a ball-and-socket connection between at least one of said terminals and said floating switch elements, and a locking device for said switch elements.

11. In a switch, the combination with a pair of spaced contact members, of a pair of floating switch elements, means affording said floating switch elements a ball-and-socket connection with one of said contact members, adjustable contact means carried by said floating switch elements for co-operation with the other contact member, tension means for causing substantially equal contact pressures on said contact members, and locking means for said floating switch elements in operative relation to one of said contact members.

12. The combination with a pair of spaced contact members, of a pair of floating switch elements, means providing a ball-and-socket connection between one of said contact members, and said floating switch element, means for limiting the maximum separation of said floating switch elements immediately adjacent to said last-mentioned contact members, and adjustable contact means for said floating switch elements permitting connection with the other of said contact members when said floating switch elements are out of alignment.

13. A switch comprising a pair of contact members, a pair of floating switch elements having a ball-and-socket connection with one of said contact members, and adjustable contacts carried by said floating switch elements in operative relation to the other of said contact members.

WILLIAM R. HUTTINGER.
